UNITED STATES PATENT OFFICE.

FREELAND W. OSTROM, OF BRIDGEPORT, CONNECTICUT.

GAGING ATTACHMENT FOR BUTTON-HOLE-STITCHING MACHINES.

SPECIFICATION forming part of Letters Patent No. 419,283, dated January 14, 1890.

Application filed March 5, 1888. Serial No. 266,209. (Model.)

To all whom it may concern:

Be it known that I, FREELAND W. OSTROM, of Bridgeport, county of Fairfield, State of Connecticut, have invented an Improvement 5 in Gaging Attachments for Button-Hole-Stitching Machines, of which the following description, in connection with the accompanying drawings, is a specification, like letters on the drawings representing like parts.

10 In stitching button-holes in wearing-ap-
parel as now most commonly done, where ac-
curacy is desirable, the material is marked to
indicate the positions for the button-holes,
and much care has to be taken by the oper-
15 ator to place the marked portions of the ma-
terial centrally in the clamp which is to hold
the material to be stitched. The marking of
the material prior to stitching it requires a
separate handling, which adds to the cost of
20 production.

In accordance with my invention the cloth-
clamp has combined with it an arm or bar
having one or more registering-gages for the
registering side of the material, the said gage
25 or gages being movable in and out of gaging
position at the will of the operator, it being
thus possible by my attachment to accurately
locate the material for the production at any
predetermined point of a button-hole.

30 An attachment employed for stitching but-
ton-holes in a cuff such as herein shown must
have its gages so constructed as to occupy
four gaging positions, two at each side the
clamp, one gaging position being that to de-
35 termine the position of that edge of the cuff
next which is to be made the button-hole to
receive the ornamental cuff-buttons, the other
position being to determine from the same
side of the cuff the location for the button-
40 hole which is to receive a button by which to
attach the cuff to the sleeve. To accommo-
date for making these button-holes in oppo-
site ends of the cuff in succession, it becomes
necessary to provide like gages at both sides
45 of the clamp.

Cuffs are commonly made in large factories
and by piece-work, the operator taking the
material after it has been marked; but with
my attachment this previous marking is un-
50 necessary, the operator, by the gaging-sur-
faces described, being enabled to put the cuff
more quickly and accurately in place than

were the mark depended upon and gages
were not employed.

Figure 1, in top or plan view partially bro- 55
ken out, represents one form of gaging at-
tachment embodying my invention, one of
the movable registering-gages being turned
or moved out of registering position, the foot- 60
plate of the registering-gage at the right be-
ing broken out to show parts below it; Fig.
2, a front elevation of the attachment shown
in Fig. 1; Fig. 3, an under side view of a por-
tion of the attachment shown in Fig. 1; Fig. 65
4, a detail showing one of the spring-catches
at the inner edge of the attachment bar or
arm. Fig. 5 represents on a small scale a cuff,
showing the positions of the button-holes to
be made in it.

The plate G and the pivoted lever or arm 70
G' above it form a cloth-clamp substantially
such as shown in United States application
No. 202,733, filed May 20, 1886, and need not
therefore be herein specifically described;
but instead of the particular clamp shown I 75
may employ any other usual or well-known
suitable form of clamp, the plate being of
course shaped to adapt it to the particular
class of machine to which the attachment is
80 to be applied.

The plate G, forming the lower member of
the cloth-clamp, has attached to it by screws
a a a lug a', forming part of a frame, the
other part of the frame consisting of arms or
bars a² a³, which, as shown in the drawings 85
in Sheet 1, support two rigid gages b b', con-
nected adjustably thereto by a screw, as b²,
and two movable or hinged gages, as c and
c'. These arms or bars at their lower side
are provided with like sliding plates b³ b⁴, 90
held thereto loosely and guided by screws e
and e², the plates having like rack-teeth, as
2, which teeth engage like teeth or projec-
tions, as 3 4, on or forming a rigid part of one
or the other of the movable registering-gages 95
c c', the said registering-gages, as shown on
Sheet 1 of the accompanying drawings, be-
ing each hinged or pivoted to a thin foot-
plate, as c², adjustably connected to the said
arms or bars a² and a³, respectively, by like 100
screws 14.

The arms or bars a² or a³ are slotted to con-
tain like spiral springs, as 5, each spring at
one end being connected with a stud, as 6, of

the slide-plates, the opposite or outer end of each spring being attached to a releasing-pin, as d or d' , the inner end of each of the said releasing-pins acting when pushed in 5 against one or the other of the like catches d^2 or d^3 , secured by screws, as 7, to one or the other of the said arms a^2 or a^3 , each catch being adapted to engage a lug or projection, as 8, upon a slide-plate b^3 or b^4 , thus holding 10 each slide-plate in with its attached spring stretched, the registering-gage, co-operating with a slide so pulled in and held, being turned down, as shown, by the gage c' , so as to not present an obstruction to resist the 15 movement of the material or to present an elevated surface over which the material would have to be bent when being clamped in position. To enable either of the said registering-gages to be elevated into gaging 20 position, it is only necessary to push upon the releasing-pin and free the spring-catch from the lug 8 engaged by it, when the spring 5 referred to will immediately assume control of and move the slide-plate outwardly 25 and move or turn up the registering-gage into registering position, the extent of outward movement of the slide-plate being determined by the screw, as e , which acts in the slot e' of the sliding-plate as a stop, the other screw, 30 as e^2 , acting as a guide for the said slide-plate, the said slide-plate and screw being alike on both arms or bars a^2 a^3 .

The clamp-base has adjustably attached to it by a set-screw f an abutting gage, as f' , 35 the said gage receiving against it one end of the cuff to be stitched.

Let it be assumed that the button-hole g in a cuff (see Fig. 5) is first to be made and that the side x^8 of the cuff is its registering 40 side. To do this the operator, without any mark on the cuff, will place the said edge x^8 against the stationary gage b , secured to the arm a^2 , the registering-gage c next to it and between it and the clamp being at such time 45 turned or moved down flat upon the arm a^2 or out of the way, so as not to form an obstruction or elevation. With the parts in this position and the cuff in normal or flat position the clamp will be closed. To work 50 the second or inner button-hole g' the operator will push the releasing-pin d and remove the spring-catch d^2 from engagement with the slide-plate b^3 , thus enabling the spring 5 to operate the slide-plate b^3 and turn 55 the registering-gage c up into registering position, this being done after the cuff has been clamped in position to properly stitch the first button-hole g . At the completion of the

button-hole g the operator will move the cuff to the left and place the registering edge 60 thereof in contact with the movable registering-gage c previously put into gaging position, and thereafter the material will again be clamped for the button-hole g' to be stitched. While working the button-holes g g' at one 65 end of the cuff, as stated, the gages at the left of the clamp are performing no function, the movable registering-gage c' being turned down out of registering position.

To stitch the button-holes g^2 g^3 at the opposite end of the cuff and in the order mentioned, so as to feed the cuff always to the left, which is merely a matter of convenience, the operator will first use the registering-gage c' , and as soon as the material is clamped 75 will turn it down or move it out of registering position, so as not to in any way obstruct the movement or clamping of the material when the button-hole g^3 is to be stitched.

For some kinds of work other than the 80 style of cuff shown one of the movable registering-gages may be omitted, and for other work one or both of the rigid gages may be omitted.

I claim--

1. The combination, with a button-hole work-clamp, of a bar or frame at the front thereof and a rigid and a movable gage on said bar or frame on each side of the button-hole slot of the said work-clamp.

2. The combination, with a button-hole work-clamp, of a bar or frame at the front thereof, a rigid gage and a movable gage on said bar or frame on each side of the button-hole slot of the said clamp, and spring-actuated sliding plates for operating said movable gages.

3. The combination, with a button-hole work-clamp, of a bar or frame at the front thereof, a rigid and a movable gage on said 100 bar or plate on each side of the button-hole slot of the said work-clamp, said movable gages being provided with teeth or projections, as 3 4, spring-actuated sliding plates, as b^3 , having teeth, as 2, to engage the teeth 105 or projections on said movable gages, and lugs, as 8, spring-catches, as d^2 d^3 , to engage said lugs, and releasing-pins to disengage said catches from said lugs.

In testimony whereof I have signed my 110 name to this specification in the presence of two subscribing witnesses.

FREELAND W. OSTROM.
